UNITED STATES PATENT OFFICE.

CHARLES GÉGAUFF AND JULES PFLIMLIN, OF MULHOUSE, FRANCE.

CLEARING MECHANISM FOR PREPARATORY MACHINES FOR TEXTILE FIBER.

Application filed July 22, 1927, Serial No. 207,794, and in Germany July 30, 1926.

The present invention relates to preparatory machines for textile fiber, and is an improvement in devices of the type shown and described in U. S. Patent No. 1,658,714, issued to us on February 7, 1928, for apparatus for cleaning revolving-flat carding machines. Such devices comprise what we have termed a clearer-roll provided with fiber-engaging teeth mounted in separate groups or successive sections, such clearer-roll thus constructed being mounted in a carding-engine between the licker-in and the forward end of the traveling-flats so that its teeth will lightly intermesh with the card-clothing of the main cylinder. The clearer-roll is rotated with the main cylinder so that through the action of its teeth the fiber that is held on the wires or teeth of the cylinder clothing will be maintained at the outer ends of said teeth, or lifted, and after passing the clearer-roll will lie in such position that when brought beneath the traveling-flats, the traveling-flats are enabled to perform properly and efficiently the function of removing impurities, the main cylinder being kept free from accumulation of fiber and dirt and stoppage for the purpose of stripping such cylinder being wholly obviated.

In the use of clearer-rolls thus formed and disposed, under some conditions a disadvantage may be experienced through their becoming themselves choked and clogged by the flying fibers, which enter the enclosing casing and are seized by the rapidly-moving teeth and become entangled therewith, so that after a time a mat of more or less compacted fiber is formed thereupon. The presence of these mats upon the clearer-rolls is prejudicial to the proper performance of their function of clearing the clothing of the main cylinder. In addition, these mats disengage themselves from time to time and are carried around by the main cylinder. When this occurs they go through, between the flats and the cylinder, without being properly worked and adversely affect the uniformity of the fleece. Thus it has been found necessary to stop the carding-engine occasionally to clean the clearer-roll itself by hand, in order to secure a satisfactory quality of output.

The object of the present invention is to overcome this difficulty and to increase the utility of the clearer-roll under the conditions named. To this end, the invention provides a clearer-roll such as aforesaid with

a shield, rotating in unison therewith, which is situated in front of each separate group or longitudinal section of teeth upon the clearer-roll, with respect to the direction of rotation thereof, so that only the working ends of the teeth project radially beyond it. The result of the use of this device is that the teeth are shielded and the flying fibers are fanned and directed outward in a general radial direction away from the axis of rotation of the clearer-roll, and escape without being seized upon the points of the teeth. Several illustrative embodiments of the invention are shown in the accompanying drawings, in which:

Figure 1 shows the preferred form of shield used in connection with a clearer-roll having a hub of relatively large diameter equipped with four separate groups or successive sections of teeth, a separate shield protecting each section;

Fig. 2 shows the preferred form of shield used in connection with a clearer-roll having a hub of relatively small diameter having teeth at the ends of radial arms arranged in two groups or sections each with an associated shield; and

Fig. 3 shows a plurality of shields used in connection with a relatively small hub clearer-roll having a single group of suitably mounted teeth.

In Fig. 1, *a* is the main cylinder of the carding-engine, *b* the clearer-roll, and *c* the enclosing casing or housing around the clearer-roll. The clearer-roll *b* has four groups of teeth *d*, of which the front part, in respect to the direction of rotating indicated by the arrow, is protected by shields *e*, affixed in any suitable manner to the surface of the clearer-roll *b* as by a tangential securing. The protecting shields *e* are so arranged that only the working ends or points of each group of teeth *d*, extend outward beyond their outer or free edges.

In Fig. 2, the clearer-roll *f* has its two groups or sections of teeth arranged diametrically opposite each other at the ends of radial arms. The shields *g*, having the same position relative to the teeth as above stated, here are usefully formed with their surfaces suitably curved. Securing to the smaller hub may be in any convenient manner.

The clearer-roll of Fig. 3 has only a single group or section *h* of teeth. A plurality of shields are employed, for example, *i*¹, *i*², *i*³, of which the shield *i*¹, situated the nearest in

front of the teeth, does not, as before, quite reach the height of the points of the teeth, and is disposed at a certain distance from the group.

5 It is obvious that the form of the shield may vary, according to the form of the clearer-roll or other device with which it is to be used, without departing from the scope of the invention as defined by the appended 10 claims. Further, it is within the scope of the invention to use it not only as a clearer for the main cylinder of carding-engines, but also wherever applicable in other fiber working processes to improve the operation of fiber- 15 engaging teeth.

Having thus described the best form of our invention at present known to us, what we claim as new and desire to secure by Letters Patent is:—

20 1. In a preparatory machine for textile fiber, a clearing roll provided with fiber-engaging teeth, said roll having a shield disposed in advance of the teeth, to direct flying fibers away from the base of said teeth.
25 2. In a preparatory machine for textile fiber, a clearing roll provided with fiber-engaging teeth, said roll having a shield mount-

ed to lie in front of said teeth in the direction of rotation, with its outer edge describing a circle of slightly less diameter than that described by the working ends of said teeth. 30

3. In a preparatory machine for textile fiber, a clearing roll provided with successive sections of fiber-engaging teeth, and a shield in spaced relation to said teeth and in advance 35 of each section.

4. A preparatory machine for textile fiber having, in combination, a card-clothed cylinder, a clearer-roll for said cylinder having clearer-teeth in successive sections, and a 40 shield in advance of each toothed section.

5. A preparatory machine for textile fiber having, in combination, a card-clothed cylinder and a housing therefor, and a rotating clearer-roll for said cylinder within said housing and having clearer-teeth, and also having a shield in advance of said clearer teeth to prevent impingement upon the teeth of the flying fibers within the housing and to fan the flying fibers out of the path of said teeth. 45 50

In testimony whereof we signed hereunto our names.

CHARLES GÉGAUFF.
JULES PFLIMLIN.
